CYRUS TAYLOR, OF HARTFORD, CONNECTICUT, AND ELMER ZEBLEY TAYLOR, OF NEWARK, NEW JERSEY

METHOD OF AND MEANS FOR THE MANUFACTURE OF CONTAINERS OF PAPER OR LIKE MATERIAL, AND LIDS OR COVERS THEREFOR

Application filed March 27, 1929. Serial No. 350,396.

The object of this invention is to provide an improved method of and means for making containers of paper or like material with straight as distinguished from tapering or 5 conical side-walls, and lids or covers therefor. It is well known that containers with straight side-walls have hitherto been made by continuously winding a tube of material in a spiral form onto a mandrel, but according to 10 the present invention it is proposed to wind such side-walls convolutely instead of spirally, and the method is such that the finished article may be of cylindrical, square or other section, while the operation is practically continuous, that is to say there is scarcely any 15 interruption in the feed of the material from a reel to the mechanism employed.

In the accompanying drawings Fig. 1 is an enlarged sectional view of part of a container 20 and lid or cover made in accordance with the present invention, and Fig. 2 a plan view of the web forming the blank therefor after it has passed the pasting device; Fig. 3 is a view 25 of the pasting device to which the web passes from the reel; Fig. 4 is an enlarged plan view showing the result obtained by the addition of the device hereinafter described for tapering off the ends of the blanks; Fig. 5 is a view 30 similar to Fig. 3 but with parts added to obtain the result shown in Fig. 4; Fig. 6 is an enlarged view of such additional parts, and Fig. 7 a greatly enlarged section of the web 35 illustrating the tapering thereof at the ends of the blanks; Fig. 8 is a view of the part of the machine to which the web of material passes from that part shown on a smaller scale in Figs. 3 and 5, and Fig. 9 is a vertical section of part thereof. Fig. 10 is a sectional view taken on the line 10—10 of Fig. 8. Fig. 40 11 is a section partly in elevation of the same, taken on the line 11—11 of Fig. 8. Fig. 12 is a section taken on the line 12—12 of Fig. 8. Fig. 13 is a section taken on the line 13—13 45 of Fig. 8. Fig. 14 is a fragmentary detail partly in elevation and partly in section of mechanism for ejecting the finished container.

Referring to Fig. 1 of these drawings it will be seen that the containers it is desired 50 to manufacture by the method and means

hereinafter described have side-walls consisting of two convolutions 1, 2, of the material employed, and that the bottom thereof consists of two discs 3, 4, between which latter the lower end 5 of the side-walls is secured. The lid or cover 6 of the container is of exactly similar construction, the side-walls being of course rolled slightly larger in diameter so that the cover will fit onto the outside of the container body. The main object of the present invention is to enable containers of this class to be made continuously from a roll of paper, in such a manner that the flow of material from such roll is continuous until the whole of the material thereof has been utilized.

In the specification of an application for patent of even date herewith Serial No. 350,394 filed by Cyrus Taylor, one of the present applicants, a method of and means for rolling tubes 70 of paper or like material is described, which is applicable to the continuous manufacture of containers of this class. The mechanism employed is shown diagrammatically in Figs. 3 and 8, where it will be seen that the web of material passes from the roll 7 to a pasting apparatus consisting of a pasting roller 8 revolving in contact with another roller 9 which dips into the paste or other adhesive contained in the paste reservoir or fountain 80 10, a squeegee roller 11 being preferably provided by which the amount of adhesive supplied by roller 9 to the actual pasting roller 8 can be regulated by means of screw 12. The 85 surface of the pasting roller 8 is mutilated in such a way that the adhesive will only be supplied to the portions of the paper web A indicated by cross lines in Fig. 2, that is to say the portion 13 which forms the interior wall of the completed container will not receive 90 any adhesive, while the narrow strip 14 will be pasted for the reason that it is to constitute the part turned into contact with the inner disc 3 of the bottom. The remaining portion 15 of this section of material will form 95 the outer ply of the completed container, and is therefore covered with adhesive. A roller 8a is preferably provided in such relation to the pasting roller 8 as to keep the web of material in proper contact therewith.

In order to avoid any unevenness in the surface of the finished article which would arise through the natural thickness of the paper, at the ends of the inner and outer laps of the blanks, it is desirable to employ the method described and claimed in the specification of an application for patent of even date herewith Serial No. 350,395 filed by Elmer Zebley Taylor, one of the present applicants, and in which this object is attained by applying considerable crushing pressure to the portions of the web which will form the ends of the blanks in such a manner that the material thereof is tapered off to comparative thinness, without being actually severed thereby. Fig. 6 of the drawings shows one method by which this result can be obtained, which it will be seen consists in the employment of a pair of rollers 40, 41, disposed as shown in Fig. 5 at a suitable point between the reel 7 from which the web of paper or other material is unwound and the pasting roller 8 by which the necessary adhesive is applied thereto. The rollers 40, 41 are rigidly mounted in respect to each other, and are driven in such relation with the other parts of the complete machine as to make a complete revolution as the proper length for the desired blank passes. Such rollers do not act to pull or feed the paper forward, but, as shown in Fig. 6, they are provided with hard steel inserts or projections 42 which, as the paper web passes the centre line between the rollers 40, 41, indent the material with such pressure that it assumes the section shown (greatly enlarged) in Fig. 7, the sloping surfaces 43 on each side tapering down to the point 44 without actually severing the material.

A modification of this arrangement may be employed in which one only of the rollers 40, 41, is provided with a steel insert or projecting part 42, the effect of which will be that the web of material will be impressed on one side only, the desired effect being however still attained. It will of course be understood that the crushing operation must not be such as to actually break the material, as this would interfere with the subsequent operation of the machine, but only sufficient to obtain the desired effect of a blank with tapered ends, enough material being left at the thinnest point to give the web sufficient strength to be carried along into the machine. In Fig. 4 of the drawings a rolled-up blank for a container or lid, and which has been treated as above described, is shown, and the improved result attained by the use of the arrangement just described will be apparent, there being a practically smooth surface on both the inner and outer sides of the article, instead of the ledges which would otherwise be presented by the natural edges of the material.

From the pasting mechanism above described the web of material A passes to one of

a series of mandrels 16 carried in a disc or holder 17 which is intermittently rotated by means of a suitable spacing mechanism. Such mandrels also have a continuous rotary movement imparted to them in their bearings in disc 17, being for this purpose formed with gear teeth 18 engaging with the internal teeth of a gear wheel 19 operated by driving pinion 20 on shaft 21, such gear wheel 19 also having external teeth with which such pinion 20 engages. Each of the mandrels 16 has formed in it a series of holes 22, these being placed in approximately the position in which the leading end of the web of material A makes contact with the mandrel. Suitable means are provided for creating a vacuum in the mandrel so that the web will be acted on thereby and so held in contact with such mandrel. The arrangement is such that after the web has thus been gripped by the mandrel the latter will make about one and a half turns, wrapping the material around it to this extent, and then the spacing mechanism hereinbefore referred to comes into action and this particular mandrel is thereby carried from position B to position C. At about this time a mechanism for breaking or severing the web between positions B and C, and consisting of an arm 23 operated by any suitable means, breaks or severs such web at a point that will leave sufficient to complete the winding of the container on the first mandrel. The outer extremity of the breaker arm 23 is preferably of such shape as to force and hold the severed end of the web in contact with the next mandrel 16 which has now arrived at position B, thus giving full opportunity for the vacuum in this mandrel to act on such severed end of the web while it in turn is being wound thereon.

In applying this arrangement in connection with that hereinbefore described for tapering off the ends of the blanks, the breaker arm 23 is caused to operate at such a time that its operating end will come in contact with the web of material A at its thinnest point, that is to say at the point 44 produced by the action of the steel inserts carried by one or both of the rollers 40, 41. The crushing operation to which the web has been subjected will facilitate the operation of breaking it at the desired point. In the drawing it will be seen that a roller 24 is shown between which and the mandrel in position B the web of material A is passed. Such roller 24 may be acted on by a spring or springs and has for its object to prevent the web from being drawn forward or being retarded, and it thus co-operates with the mandrel 16 at the time in position C to place sufficient tension on the web to enable the breaker arm 23 to sever the latter. This arrangement permits the object hereinbefore referred to, viz—the continuous manufacture of this class of convoluted wound containers, to be attained,

as there is a slightly intermittent continuous feed of the material from the reel until the whole of such material has been utilized.

To supply the inner one, 3, of the two discs which constitute the end of the container, suitable means may be provided at the point G for cutting such disc from a web of suitable material and for applying it to the end of the mandrel 16 then in that position, where it will be held by suction through holes 22^a in such end. Cut and feeding means for the disc 3 may include feeding rollers 50 intimately driven in proper timed relation with other parts of the machine to feed a strip of material 51 to a punch and die 52 and 53 respectively, the same being located adjacent the end of the cylinder at position G. A crank 54 is properly driven and timed to cut the disc and presented to the cylinder 16 to be gripped thereto by suction created in the cylinder. It will be retained there while such mandrel moves from position G to position B and then on to position C, suction having been established and maintained throughout this movement through a port 55 formed in the member 17, one for each cylinder, said port communicating with the interior of the cylinder at one end and with the segmental groove 56 formed in a header 57, the groove extending, as shown, from the position of station G to that of station C. The groove 56 is connected to a vacuum pump through the pipe 58 threaded into the header. At position C the winding of the side-walls 1, 2, on the mandrel will be completed, such side-walls being so disposed in relation to the mandrel that a sufficient length thereof, about corresponding to the width of the narrow pasted portion 14 (Fig. 2) will project beyond the end of the mandrel and the disc 3 carried thereby. This projecting end of the side-walls 1, 2, is turned over into contact with the disc 3 on the end of the mandrel when the latter, in the intermittent movement imparted to the holder 17, arrives at the position C. A roller 59 having a flange 60 is mounted for free rotation on an arm 61, which arm in turn is pivoted at 62 to the frame of the machine. The flange 60 engages the projecting end of the side wall of the container and forces it into engagement with a disc 3 as shown in Fig. 11. Any other suitable means may be employed for this purpose, it being of course understood that the object of this turning over is to bring the narrow pasted portion 14 of the side-walls into intimate contact with the disc 3 and cause it to adhere thereto. The paste or other adhesive employed should be of a quick drying character, so as to overcome any tendency of the turned-over side-wall to leave the disc after it has been brought into contact therewith.

The intermittent movement of holder 17 next brings the mandrel 16 in question to the position F, where mechanism is provided for

cutting the other or outer disc 4 from a web of material, said material having applied thereto a suitable adhesive, and then bringing the latter with considerable pressure into contact with the disc 3 and the turned-in portion of the side-walls 1, 2, such turned-in portion being thus securely held between the two discs. The mechanism indicated generally by the numeral 63 for performing this operation is a duplication of the mechanism for cutting and feeding the disc 3, the same numerals carrying the suffix a being applied to like parts and it is thought the description relating to the former mechanism will suffice for this, the feeding rollers of both devices being simultaneously operated by suitable gearing 64. If desired the mechanism for bringing the disc 4 to position and causing it to adhere may also form a bead or other configuration thereon, to improve the appearance of the finished article and assist in retaining the disc in position. It will be readily understood that although the machine may as above described include means for cutting the discs 3, 4, from webs of material, such cutting may if found desirable be effected separately, the remaining operations as described being then conducted with discs supplied in any suitable manner.

Subsequent movement of the holder 17 brings the mandrel 16 with the now finished container to the position F, where a delivery mechanism will act on such container to eject it from the mandrel. This operation may be performed by a ring 65 caused to slide along the latter, and it will be found advisable to assist the operation of this ring by causing a pressure of air through the perforations in the mandrel, as otherwise a vacuum would be formed therein which would operate to prevent the removal of the container. A yoke 66 pivoted at 67 and connected to the ring 65 through a pin and slot connection 68 has an arm 69. The pivotal connection 67 is located in a lug projecting outwardly from a ring 70 secured to and rotating with the member 17. A spring 71 returns the ring to its normal position after ejection of the finished article.

It will be understood that each cylinder is provided with an ejecting device as above described. A plunger 72 is located adjacent the position F and as a cylinder comes to rest at this station, said plunger overrides the end of the arm 69. A cam 73 is operated at the proper time and the yoke 66 swung on its pivot 67, the ring 65 thereby expelling the finished receptacle. Coincident with the movement of the lever 69 under the plunger 72 the port 55 is brought into registration with an opening 74 in the header 57. Air under pressure is introduced from a pipe line 75 to assist in the removal of the article as hereinbefore described. After the container has been thus removed the intermittent movement of holder 17 brings the particular man-

drel the operation of which has been followed back to the position G, where another disc will be applied thereto and the operation continued. The intermittent movement described may be imparted to the holder 17 in any suitable manner, the means shown in the drawing consisting in a series of slots 25 formed in such holder and with each of which in turn engages a roller 26 carried on a continuously rotating disc 27, receiving its motion by suitable gearing 28, 29, from the main shaft. The disc 27 also carries a cam 30 which operates a locking arm 31 having a tooth 32 adapted when the holder 17 is stationary to enter one of a series of notches 33 for the purpose of preventing any movement of such holder while the various operations are being performed on the container.

As above described the side-walls of the articles would consist of two convolutions or plies of material, but it will be readily understood that by suitably modifying the relation of the spacing mechanism to the driving mechanism for the mandrels, articles having side-walls of three or more convolutions or plies of material can be produced by the method described. If desired mechanism may be provided between the reel 7 from which the web of material A passes, and the pasting mechanism, for the purpose of printing such web in one or more colours. The above description applies particularly to the body of the container, but reference to Fig. 1 will show that the lid 6 therefor is of precisely similar construction, such lid being, as will be understood, made of slightly larger diameter so that it will fit tightly onto the body. It will also be readily understood that although the invention has been described and illustrated in connection with the manufacture of cylindrical containers, by suitably modifying the shape of the mandrels or formers on which the web of material is wound, it is possible to manufacture square, rectangular or other shaped containers by this improved method, the shape of the discs or blanks forming the ends of the container or lid being in this case of course correspondingly modified.

What we claim and desire to secure by Letters Patent is:—

1. The combination in a container-making machine of a pasting device adapted to apply adhesive to a web of material, series of mandrels mounted on an intermittently rotated holder, means for rotating such mandrels and thus winding the web convolutely thereon, means active prior to the winding for crushing the web at suitable points to cause the ends of the blanks to be tapered off to a comparatively thin edge, means for severing the web at such points after it has been partially wound on one of the mandrels, means for creating a vacuum within the mandrels whereby the severed end of the web will be

drawn to and held by the mandrel during the winding operation, and means for cutting a disc of material for the end of the article and applying it to the end of the mandrel and causing it to be held there by the vacuum. 70

2. The combination in a container-making machine of a pasting device adapted to apply adhesive to a web of material, a series of mandrels mounted on an intermittently rotated holder, means for rotating such mandrels and thus winding the web convolutely thereon, means active prior to the winding for crushing the web at suitable points to cause the ends of the blanks to be tapered off to a comparatively thin edge, means for severing the web at such points after it has been partially wound on one of the mandrels, means for creating a vacuum within the mandrels whereby the severed end of the web will be drawn to and held by the mandrel during the winding operation, means for applying a disc of material to the end of the mandrel and causing it to be held there by the vacuum, and means for turning in the end of the side-walls of the article into contact with the outer side of such disc. 80

3. The combination in a container-making machine of a pasting device adapted to apply adhesive to a web of material, a series of mandrels mounted on an intermittently rotated holder, means for rotating such mandrels and thus winding the web convolutely thereon, means active prior to the winding for crushing the web at suitable points to cause the ends of the blanks to be tapered off to a comparatively thin edge, means for severing the web at such points after it has been partially wound on one of the mandrels, means for creating a vacuum within the mandrels whereby the severed end of the web will be drawn to and held by the mandrel during the winding operation, means for applying an inner disc of material to the end of the mandrel and causing it to be held there by the vacuum, means for turning in the end of the side-walls of the article into contact with the outer side of the said inner disc, and means for cutting an outer disc of material and applying it over the inner disc and the turned-in part of the side-walls. 100

4. The combination in a container-making machine of a pasting device adapted to apply adhesive to a web of material, a series of mandrels mounted on an intermittently rotated holder, means for rotating such mandrels and thus winding the web convolutely thereon, means active prior to the winding for crushing the web at suitable points to cause the ends of the blanks to be tapered off to a comparatively thin edge, means for severing the web at these points after it has been partially wound on one of the mandrels, means for creating a vacuum within the mandrels whereby the severed end of the web will be drawn to and held by the mandrel. 110

10 during the winding operation, means for applying an inner disc of material to the end of the mandrel and causing it to be held there by the vacuum, means for turning in the end of the side-walls of the article into contact with the outer side of said inner disc, means for applying an outer disc over the inner disc and the turned-in part of the side-walls, and means for ejecting the finished article 15 from the mandrel.

15 5. The combination in a container-making machine of a pasting device adapted to apply adhesive to a web of material, a series of mandrels mounted on an intermittently rotated holder, means for rotating such mandrels and thus winding the web convolutedly thereon, means active prior to the winding for crushing the web at suitable points to 20 cause the ends of the blanks to be tapered off to a comparatively thin edge, means for

subsequently severing the web at such points after it has been partially wound on one of the mandrels, means for creating a vacuum within the mandrels whereby the severed end of the web will be drawn to and held by the 70 mandrel during the winding operation, means for applying an inner disc of material to the end of the mandrel and causing it to be held there by the vacuum, means for turning in the end of the side-walls of the article into 75 contact with the outer side of said inner disc, means for applying an outer disc over the inner disc and turned-in part of the side-walls, means for ejecting the finished article 80 from the mandrel, and means for assisting such ejection by air pressure produced in the mandrel.

In witness whereof we have signed this specification.
